LEG REST

William F. Williams, St. Clair Shores, Mich., assignor to Yorna L. Malcolm, St. Clair Shores, Mich.

Application August 7, 1957, Serial No. 47,262

Term of patent 14 years

(Cl. D15—8)

Fig. 1 is a perspective view of a leg rest, showing my design.

Fig. 2 is a similar view thereof taken from a different angle.

Fig. 3 is a front elevational view thereof with the pivoted member upright.

Fig. 4 is an enlarged cross-sectional view taken on line 4—4 of Fig. 1.

I claim:

The ornamental design for a leg rest, substantially as shown.
